UNITED STATES PATENT OFFICE.

HAROLD A. WEBSTER, OF HAVERHILL, ASSIGNOR OF ONE-HALF TO LEWIS F. TENNEY, OF BOSTON, MASSACHUSETTS.

LEATHER-CLEANING MACHINE.

SPECIFICATION forming part of Letters Patent No. 407,310, dated July 16, 1889.

Application filed January 12, 1889. Serial No. 296,138. (No model.)

To all whom it may concern:

Be it known that I, HAROLD A. WEBSTER, of Haverhill, in the county of Essex and State of Massachusetts, have invented certain new 5 and useful Improvements in Leather Brushing or Cleaning Machines, of which the following is a specification.

This invention has for its object to provide improved means for cleaning and brightening the uppers of boots or shoes or other articles of leather or other material in factories, to remove finger-marks and other stains incidental to the processes of manufacture, and to give the surface a bright and attractive 15 appearance.

In performing the operation it is found that the best results are produced by using a rapidly-rotating moistened brush. Much difficulty has been experienced in keeping the 20 brush properly moistened. If its bristles dip directly in the water, the water is taken up in such quantities that it forms in drops, which are rapidly thrown off by centrifugal force.

25 My invention relates, chiefly, to means for applying water so thinly and evenly to the brush that it cannot collect in drops or masses of sufficient weight to be thrown off centrifugally; and to this end it consists in a wick 30 or other absorbent body adapted to conduct water from a reservoir by capillary action, combined with a rotary brush, the wick being in contact with the periphery of the brush.

The invention also consists in certain minor 35 improvements, all of which I will now proceed to describe and claim.

In the accompanying drawings, forming a part of this specification, Figure 1 represents a front elevation of an organized machine 40 embodying my improvements. Fig. 2 represents a section on line $x-x$, Fig. 1.

The same letters of reference indicate the same parts in both the figures.

In the drawings, a represents a circular 45 brush mounted on a shaft b , which is journaled in bearings in a supporting-frame.

c represents a water-tank below said brush, and d represents a capillary conductor or feeder of wicking, sponge, or other suitable 50 material, having one end in contact with the water and the other end in contact with the

periphery of the brush. Means may be provided for adjusting said wick or conductor, and to this end a tube may be provided to hold the wick, and one or more adjusting- 55 ratchets, such as are used for lamp-wicks. I prefer, however, to present the side of the wick to the brush, and to hold the wick on a curved bed d' , Fig. 2, by means of ears e' , Fig. 1, formed on said bed. 60

The tips of the bristles of the rapidly-rotating brush moving over the saturated wick become moistened uniformly without collecting an excess of water, so that the water is not thrown off but remains on the brush material and acts on the upper or other article which is presented to the brush at the point 2. The action of the rapidly-moving moistened bristle or brush tips on the leather is such as to rapidly clean and brighten the 70 same without removing any of the finish thereof, and without leaving it too damp.

I prefer to provide two brushes, located side by side on the same shaft, one of the brushes being operated in a dry and the other 75 in a moist condition, thus enabling the operator, without change of position, to present the upper to the damp brush and to the dry brush in succession, the latter acting to remove all moisture from the leather and impart a final 80 luster thereto. I prefer to arrange a scraper or gutter i in such proximity to the periphery of the damp brush that it will collect therefrom the blacking and dirt with a portion of the water that the brush material has taken 85 up. Said scraper or gutter is arranged with one edge close to the periphery of the brush, just above the point where the upper is presented to the brush, so that the brush material is deprived of said matter before it comes 90 in contact with the upper. A tube j , preferably flexible, conducts away the water and other matter removed by the scraper from the brush and discharges the same at any convenient point, as into a bucket k .

The 95 scraper is adjustable so that it may be moved toward the axis of the brush to compensate for wear of the brush material; or may be moved away from the periphery of the brush when its use is not required. The means here 100 shown for adjusting the scraper are screws i' , j' , mounted to rotate in a bracket on the sup-

porting-frame and engaged with nuts n on the scraper.

I have here shown a moistening wick or conductor, and a scraper for each brush, the wick and scraper of the dry brush being preferably adjusted so that they are not in contact with the periphery thereof. This arrangement enables either brush to be used wet or dry, so that in case one brush becomes wet or dirty the wick of the other brush can be adjusted to moisten the latter, the machine being run without using the previously wet brush until it has been dried.

The wick or feeder supporting bed d' may be adjusted backwardly to remove the wick from the brush when it is desired to avoid moistening the latter.

I do not limit myself to a machine having two brushes, nor to the conjoint use of a conductor or feeder and a scraper with a brush, as the scraper can be dispensed with. Better results are produced, however, when the scraper is used. The brush material is preferably ordinary bristles, such as are commonly used for brushes of various kinds.

I claim—

1. In a leather brushing or cleaning machine, the combination of the tank or reservoir having the bed or support mounted thereon, the feeder having one end in the tank and the other end supported on the bed, and the brush adapted to revolve against the feeder, substantially as described.

2. In a leather brushing or cleaning machine, the combination of the tank, the guide or bed on said tank, the brush adjacent to said guide, and the wick having one end in the tank and the other end resting on the guide and in contact with the brush, substantially as and for the purpose described.

3. In a leather brushing or cleaning machine, the combination of the tank or reservoir, the brush arranged above said reservoir, the wick having one end in the reservoir and the other end in contact with the brush, and the scrapers arranged above and in contact with the brush, substantially as and for the purpose described.

4. In a leather brushing or cleaning machine, the combination of a tank or reservoir, brushes arranged above said reservoir, wicks leading from the reservoir to said brushes, scrapers having gutters for removing the surplus liquid from the brushes, and a pipe or tube communicating with the gutters for conducting the liquid therefrom, substantially as and for the purpose described.

In testimony whereof I have signed my name to this specification in the presence of two subscribing witnesses, this 29th day of December, 60 A. D. 1888.

HAROLD A. WEBSTER.
